(57) **CLAIM**

The ornamental design for tablet accessory for personal electronic devices, as shown and described.

DESCRIPTION

FIG. 1 shows an elevated perspective view of a tablet accessory for personal electronic devices in accordance with my invention;

FIG. 2 illustrates an exploded view showing three separated components comprising my invention as depicted in the assembled representation of FIG. 1;

FIG. 3 depicts a plan, top view showing a tablet screen provided on an opposite side of the invention illustration of FIG. 1;

FIG. 4 represents a side view taken along a long side of FIG. 1, the opposing side being a substantial mirror image of the same;

FIG. 5 represents a side view taken along a short side of FIG. 1, the opposing side being a substantial mirror image of the same; and,

FIG. 6 depicts a plan view of the bottom, exposed side of my invention as shown in FIG. 1.

The phantom line portions being provided to show the environment of the invention form no part of the claimed subject matter.
